(57) **CLAIM**

The ornamental design for a safety razor tray, as shown and described.

DESCRIPTION

FIG. 1 is a top front perspective view of a safety razor tray showing our new design;

FIG. 2 is a front elevation view of the safety razor tray shown in FIG. 1;

FIG. 3 is a rear elevation view of the safety razor tray shown in FIG. 1;

FIG. 4 is a left side elevation view of the safety razor tray shown in FIG. 1;

FIG. 5 is a right side elevation view of the safety razor tray shown in FIG. 1;

FIG. 6 is a top plan view of the safety razor tray shown in FIG. 1; and

FIG. 7 is a bottom plan view of the safety razor tray shown in FIG. 1.

FIG. 8 is a first perspective view of a safety razor tray showing another embodiment of our new design with a selectively moveable leg in a first retracted position;

FIG. 9 is a second perspective view of the safety razor tray shown in FIG. 8 with the movable leg in a second deployed position allowing the tray to stand upright on its rear end;

FIG. 10 is a front elevation view of the safety razor tray shown in FIG. 8;

FIG. 11 is a rear elevation view of the safety razor tray shown in FIG. 8;

FIG. 12 is a side elevation view of the safety razor tray shown in FIG. 8;

FIG. 13 is a side elevation view of the safety razor tray shown in FIG. 9;

FIG. 14 is a top plan view of the safety razor tray shown in FIG. 8; and,

FIG. 15 is a bottom plan view of the safety razor tray shown in FIG. 8.
